CLAIM

The ornamental design for a display screen with transitional graphical user interface, as shown and described.

DESCRIPTION

1. Display screen with transitional graphical user interface
Reproduction 1.1 is a front view of a first image in a sequence for a display screen with transitional graphical user interface;

Reproduction 1.2 is a second image thereof;
Reproduction 1.3 is a third image thereof; and
Reproduction 1.4 is a fourth image thereof.

The appearance of the transitional image sequentially transitions between the images shown in Reproductions 1.1-1.4. The process or period in which one image transitions to another image forms no part of the claimed design; The broken lines in the figures illustrate the environment and form no part of the claimed design; The broken line showing of a display screen forms no part of the claimed design; The shading illustrates a contrast in appearance.
